UNITED STATES PATENT OFFICE.

HARRY AINSWORTH, OF MOLINE, ILLINOIS, ASSIGNOR TO WILLIAMS, WHITE & COMPANY, A CORPORATION OF ILLINOIS.

MACHINE FOR PUNCHING HOLES IN METAL.

1,016,120.

Specification of Letters Patent. Patented Jan. 30, 1912.

Application filed April 22, 1911. Serial No. 622,842.

To all whom it may concern:

Be it known that I, HARRY AINSWORTH, a citizen of the United States, residing at Moline, in the county of Rock Island and 5 State of Illinois, have invented certain new and useful Improvements in Machines for Punching Holes in Metal, of which the following is a specification, reference being had therein to the accompanying drawing.

10 My invention relates to machines for punching holes in metal, such for example as steel plates or bars or other shapes, and more especially to metal punching machines having a number of sets of dies and punches 15 arranged in two or more spaced-apart rows.

An object of my invention is to provide an effective and durable means of holding down the metal plate or other work upon the withdrawal of the punch, or as it is referred 20 to, stripping the work from the punches; and another object is to afford a design and construction of machine including the said stripping device or hold-down.

Other objects will appear in the following specification.

The invention for carrying out these objects consists in the novel machine and the elements and combinations therein shown and described in the following specification 30 and the drawings thereof.

In the accompanying drawings forming a part of this specification, Figure 1 represents a front view of a metal punching machine; and Fig. 2 is a cross-section taken 25 on a plane extending from front to rear.

The machine shown herein for punching two or more spaced-apart rows of holes, is one comprising a reciprocating ram or head which carries and thereby operates the 40 punches of both rows, and in connection therewith a stripper or hold-down device supported in the machine's frame and comprising a single stripper bar having parts thereof or extensions therefrom arranged 45 for holding the work down against the withdrawal of the punches in both rows.

One important feature of the invention is a single stripper or hold-down centrally located and supported in the frame of the 50 machine in connection with a reciprocating ram or head whose underside is recessed or cut away so as to accommodate the non-reciprocating stripper bar.

Referring now to the drawings, there is 55 a frame A having a lower jaw or table a

and end frame parts a' of a curved shape so as to afford an upper jaw carrying the fittings of the reciprocating ram. Mounted on the lower jaw a is a lower bolster or die holder B, and on this are carried the forward 60 row of dies C and the rear row of dies D, the upper surfaces of said dies forming a support for the work such as a sheet of steel X to be punched with a double row of holes. Each die has an interior passage c, d, for 65 carrying the punchings or slugs to a convenient spot on the floor of the shop. Above and opposed to the dies C, D, is a punch operating ram E fitted in a convenient manner to slide upwardly and downwardly as 70 in slots indicated at e in the end frame parts a'. For reciprocating the ram there may be employed a shaft e' having an exterior gear e² driven by power in any convenient manner; said shaft e' having bearings in the end 75 frame parts and also in two standards e³, e⁴, secured to the machine frame A. In proper locations on shaft e' are mounted, for example, three eccentric disks e⁵, only two of which are seen in Fig. 1, and surrounding 80 said disks are three eccentric rings e⁶ which have downward extensions connecting them at e⁷ to the ram E, whereby the rotation of shaft e' effects the up and down sliding movements of the ram.

The machine is shown as of a type in which the punches are operated by the reciprocating ram not through the striking of the punches by the ram but through the punches being carried directly on or with the ram in 90 its movements or indirectly through an interposed part. Thus F indicates a front row of punches and G a rear row, and each of the punches, for example F, is connected with the ram in the following convenient 95 manner.

f represents a punch holder having an interior socket accommodating the punch F, and said holder is secured as by bolts directly to the reciprocating ram. In this way 100 the downward movement of the ram carries the punch F with it and the latter being directly opposed to the die C underlying it, is caused to force a piece of metal out of the plate X and form a hole therein.

In a punching machine of this type it is convenient to employ in connection with each punch a device known as a gag H having a handle h for pushing it in and pulling it out, its purpose being when pushed 110

in to stand over the head of the punch, as indicated in dotted lines in Fig. 2, and cause it to operate, and when pulled out to render the punch inoperative by affording leeway for relative upward movement of the punch with respect to the holder so that the ram and holder may descend without forcing the punch through the work.

The stripper or hold-down device of my invention is one which is adapted to hold-down the work X against the withdrawal of both rows of punches F, G, and to this end I have shown a stripper or hold-down J located centrally or between the two rows 15 of punches. The stripper J is not a movable device although it may be adjustable and it is secured to the frame of the machine or a part thereof such as the projection j specially provided for that purpose 20 at each end of the machine. The ends of the stripper or bar J may be slotted as indicated at j' and the stripper connected to the projection j by means of bolts j², j², there being a metal block or liner j³ inserted 25 between the top of the stripper bar and the overhanging portion j⁴ of projection j so as to solidly and rigidly hold the stripper bar in position against upward displacement.

In order that the stripper hereof may hold 30 down the work adjacent to both rows of punches while the latter are withdrawing, it may be formed to engage the work at those points or may be provided with rows or series of extensions, such for example as the 35 front extensions K, extending toward the front row of punches, and the rear extensions L, extending toward the rear row of punches, these extensions and the stripper bar J together constituting the stripper or 40 hold-down device of this invention.

According to the machine of this invention, there is a special relation between the stripper and the reciprocating ram. The latter has been described as of a type carrying 45 the punches, and the heavy or body portions of the ram in their downward movements extend so nearly to the work as not to require a great length of punch and so as to give the greatest and best effect in 50 punching and render the machine more durable than it would be with a different type of ram. On the other hand the stripper is shown as of a heavy stalwart construction with considerable vertical dimension so 55 that it may exert the very large resistance that is necessary to oppose the lifting of the punches and to properly hold down the work and strip it from the punches. The ram is shown recessed or cut away at M at 60 its underside to a very considerable degree, thus constituting the two lower ram portions m, m; between which is the recess M. Said recess is of such size and location as to receive and accommodate the bar of the 65 stripper J and give plenty of room for the

ram's reciprocation; whereas on the other hand the stripper with its substantial vertical dimension is of such width and location as to be easily accommodated within the recess M of the ram. In this way all 70 conflict is avoided between the different members of the machine, and at the same time all of the advantages pertaining to each member is fully retained and enhanced as set forth.

All of the dies C, D, the punches, F, G, and the stripper extensions K, L, are seen to be of comparatively short lengthwise dimension, that is, lengthwise of the machine, this permitting longitudinal adjustment 75 thereof, and all of said members C, D, F, G, K, L, are shown as longitudinally adjustable so that the positions of the holes may be varied and all the parts set properly to coöperate; such means of adjustment consisting of clamping bolts N for the several 80 members with heads n engaging slots formed at n' in the machine parts to which the members are secured, said bolts having nuts n² for locking the same in place.

I do not wish to be limited to the specific details shown and described, as obvious modifications are possible within the spirit 85 of my invention.

What I claim and desire to secure by Letters Patent is:

1. A machine for punching holes in metal, including in combination, the machine frame, a plurality of spaced-apart rows of dies and punches, a reciprocating ram or 100 head carrying and operating the punches in both rows, and an unelastic stripper or hold-down bar of considerable vertical dimension and rigidly held at its ends by said frame, said bar having means for holding 105 the work against the withdrawal of both rows of punches, and said bar located centrally between two rows of punches.

2. A machine for punching holes in metal, including in combination, the machine frame, a plurality of spaced-apart rows of dies and punches, a reciprocating ram or 110 head carrying and operating the punches in both rows, and a stripper or hold-down supported by said frame comprising a single 115 stripper bar having means for holding the work against the withdrawal of both rows of punches, and said stripper bar located centrally between two rows of punches and having forward and rearward stripper ex- 120 tensions.

3. A machine for punching holes in metal, including in combination, the machine frame, a plurality of spaced-apart rows of dies and punches, a reciprocating ram or 125 head carrying and operating the punches in both rows, and a stripper or hold-down supported by said frame comprising a single stripper bar having means for holding the work against the withdrawal of both 130

rows of punches, and said stripper bar located centrally between two rows of punches and having forward and rearward stripper extensions; and each die, punch and stripper extension being of short lengthwise dimension, longitudinally adjustable and clamped in position.

4. A machine for punching holes in metal, including in combination, the machine frame, a plurality of spaced-apart rows of dies and punches, a reciprocating ram or head carrying and operating the punches in both rows, gag sockets and gags intermediate the ram and punches, and a single stripper or hold-down supported by said frame for holding the work against the withdrawal of both rows of punches, said stripper comprising a stripper bar of considerable vertical dimension located centrally or between two rows of punches, and the underside of the ram being recessed or cut away affording a space in which the stripper bar is accommodated.

5. A machine for punching holes in metal,

including in combination, the machine frame, a plurality of spaced-apart rows of dies and punches, a reciprocating ram or head carrying and operating the punches in both rows, gag sockets and gags intermediate the ram and punches, and a single stripper or hold-down supported at its ends by said frame for holding the work against the withdrawal of both rows of punches, said stripper comprising a stripper bar of considerable vertical dimension located centrally or between two rows of punches, and the underside of the ram being recessed or cut away affording a space in which the stripper bar is accommodated.

In testimony whereof I affix my signature in presence of two witnesses.

HARRY AINSWORTH.
